UNITED STATES PATENT OFFICE.

LEON TEALE, OF NEW YORK, N. Y.

FUSE.

1,321,949.

Specification of Letters Patent. Patented Nov. 18, 1919.

Application filed June 12, 1919. Serial No. 303,555.

To all whom it may concern:

Be it known that I, LEON TEALE, a citizen of the United States, and a resident of New York city, in the county of New York 5 and State of New York, have invented certain new and useful Improvements in Fuses, of which the following is a specification.

This invention relates to electrical cartridge fuses and particularly to that type 10 in which the fuse element may be readily removed and replaced when desired or a new one inserted when the previous one melts or burns out. In such constructions there is commonly provided a cylindrical 15 body of insulation material with metallic caps or other terminals connected within the body of the cartridge by the fuse element. It has been proposed to provide the peripheral wall of the cartridge with a slot or 20 aperture through which the new fuse may be inserted and secured in place and which slot may be covered by an outer sleeve having a corresponding slot which may be brought into or out of registry with that in 25 the body to open or close the casing. One object of my invention is to so mount the sleeve that there is little or no liability of the latter being rotated to expose the fuse during shipment or handling of the same. 30 I accomplish this result by mounting the rotatable sleeve inside of the casing rather than upon the exterior so that in handling the cartridge one does not take hold of the sleeve and therefore is not liable to rotate 35 it. I also provide as an important feature of my invention, simple and efficient means for operating this internal sleeve and locking it in closed position so as to prevent any jarring, vibration, or handling of the fuse 40 from opening up the cartridge.

In the accompanying drawings to which reference is to be had, I have illustrated one embodiment of my invention although I do not wish to be limited to this particular form 45 except in so far as defined in the appended claims.

In these drawings:

Figure 1 is an elevation of the device, the cartridge being closed. 50 Fig. 2 is a view similar to Fig. 1 but showing the cartridge open, small portions being broken away to show certain details of construction.

Fig. 3 is an edge view with the cartridge 55 open.

Fig. 4 is an end view, and

Figs. 5 and 6 are transverse sections on the lines 5—5 of Fig. 2, and 6—6 of Fig. 3, respectively.

In the specific form illustrated, the cartridge or casing includes a cylinder 10 of fiber or other suitable insulation material closed at its ends by metallic caps 12. The caps include end walls which may be perforated, if desired, as shown in Figs. 4, 5, 65 and 6, and cylindrical walls into which the ends of the fiber cylinder 10 telescope. The caps are rigidly attached to the cylinder in any suitable manner, the attaching means illustrated including a pair of removable 70 screws 13—13 for each cap. Any other suitable means may be employed.

Extending inwardly from the end walls of the two caps are terminals 14 in the form of metallic lugs which may be connected by 75 a fuse 15. As shown, this fuse is in the form of a piece of fuse wire, the opposite ends bent to form loops through which locking screws 16 may extend into threaded 80 apertures in the lugs or terminals 14. The fuse thus connects the two caps 11, 12 and these may be so constructed as to directly engage with the sockets or other terminals between which the fuse is to be inserted. I have shown the lugs 14 formed integral with 85 blade terminals 17, 17 as is common in this general type of cartridge fuse. These blade terminals may have shoulders abutting against the outer surface of each end wall and may have portions swaged or riveted 90 over into engagement with the inner surface of the end wall of the cap to hold the parts rigid in respect to each other. This constitutes no portion of my invention and may be modified within wide limits. The lugs 95 14 may be of any suitable construction adapting them to receive or have attached thereto any suitable form of commercial replaceable fuse.

The insulation casing 10 has an aperture 100 18 extending the full length between the two caps and of a width equal to one-fourth or one-third of the periphery of the casing. Within the casing I provide a sleeve 19 also 105 of fiber or other insulation material and having a slot or aperture 20 extending lengthwise thereof and of approximately the same width or circumferential extent as the slot 18. This inner sleeve may be rotated to bring the slots into registry as indicated in 110

Figs. 2 and 5 or to bring them out of registry and close the casing as indicated in Fig. 1. When this internal sleeve is rotated to open position, the screws 16 are readily accessible and the fuse 15 may be removed or a new one readily inserted. When the sleeve is moved to closed position, only a comparatively small amount of its external surface is exposed. Thus in grasping the cartridge 10 by the center portion to insert the blade terminals in their sockets, there is very little liability of rotating the sleeve to open position.

In order to facilitate the easy operation 15 of this internal sleeve one of the caps, as for instance, the cap 12 has its peripheral wall provided with a slot 21 and the cylindrical wall 10 of the casing has a corresponding slot out through which extends an operating 20 and locking member 22 from the inner sleeve. This member is shown in the form of a screw 22 threaded into the sleeve in such position that when the screw is at one end of the slot, the apertures 18 and 20 will 25 be in registry as shown in Figs. 2 and 5 and when at the opposite ends of the slot, they will be out of registry and the casing will be closed as shown in Fig. 1. The screw 22 may have an ordinary slotted, rounded head 30 which is sufficient for the application of lateral pressure to rotate the sleeve. With the sleeve in closed position, the operator may give the screw 22 a partial turn which will bind the head against the outer surface of 35 the cap 12 and effectively hold the sleeve against any accidental return rotation by jarring or vibration. The screw may, if desired, be normally kept partially tightened so that it will give a frictional resistance 40 and prevent the free rotation of the sleeve but permit of such rotation when sufficient lateral pressure is applied to the screw without rotating the latter. So far as its functions as an operating means is 45 concerned, projecting members other than the screw 22 might serve the same purpose.

Having thus described my invention, what I claim as new and desire to secure by Letters Patent is:

50 1. In an electric fuse of the cartridge type, the combination of a cylindrical shell having an aperture therein, caps at each end of

said shell, conductors secured to said caps, a fuse connecting the inner ends of said conductors, and an inner sleeve rotatable within 55 said shell and having an aperture adapted to be moved into and out of registry with the aperture in the shell.

2. An electric fuse of the cartridge type, having a cylindrical casing of insulation 60 material, caps telescoping with and receiving the ends of said casing, terminals secured to the end walls of said caps and projecting inwardly, a fuse connecting said terminals, a sleeve within said casing, said 65 sleeve and casing having apertures which may be brought into and out of registration upon the rotation of said sleeve, and a member secured to said sleeve and projecting through said casing for rotating said sleeve. 70

3. A cartridge fuse having a cylindrical wall of insulating material, having a longitudinal aperture and a circumferentially extending slot, a sleeve within said casing having a longitudinal aperture adapted to 75 be brought into or out of registration with the aperture of said casing, an operating member secured to said sleeve and projecting through said slot, caps closing the opposite ends of said casing, and a fuse within 80 said casing and detachably secured to said caps.

4. A cartridge fuse including a cylindrical wall of insulating material having an aperture extending along one side thereof, 85 and a circumferentially extending slot adjacent to one end, a sleeve within said wall and having a longitudinally extending aperture adapted to be brought into or out of registration with the aperture of the wall, a 90 screw extending through said slot into said sleeve and adapted to serve as an operating member to rotate said sleeve and when tightened serving to lock said sleeve in adjusted position, caps closing the ends of 95 said cylindrical wall, and a fuse detachably secured to said caps, the securing means being accessible through said apertures when the latter are in registry.

Signed at New York city, in the county of 100 New York and State of New York, this 11th day of June, A. D. 1919.

LEON TEALE.
